UNITED STATES PATENT OFFICE.

GEORGE A. TERRY, OF BUFFALO, NEW YORK.

DESIGN FOR A BOTTLE HOLDER.

Application filed February 4, 1925. Serial No. 12,259. Term of patent 3½ years.

To all whom it may concern:

Be it known that I, GEORGE A. TERRY, a citizen of the United States, residing at Buffalo, in the county of Erie and State of New York, have invented a new, original, and ornamental Design for Bottle Holder, of which the following is a specification, reference being had to the accompanying drawing, forming part thereof.

In the accompanying drawing, the figure is a perspective view of a bottle holder showing my new design.

I claim:

The ornamental design for a bottle holder, as shown.

GEORGE A. TERRY.
